TREMULANT ATTACHMENT FOR
ACCORDIONS

Michele De Bellis, New York, N. Y.

Application June 8, 1939, Serial No. 278,146

2 Claims. (Cl. 84—376)

This invention relates to a tremulant attachment for accordions which will automatically cause the accordion to sound with a tremulous tone. This tremulant operates without the use 5 of any electric current or electric energy of any kind.

It is an object of the invention to provide an attachment of the above mentioned character which may be installed in the conventional accordion without material alterations and which embodies means for eliminating the tremulous effect at the will of the operator.

A further object of the invention is to provide an attachment of the above mentioned character 15 which is simple and durable in construction, reliable and efficient in operation and inexpensive to manufacture.

Another object of my invention is to so design such mechanism that the same movement of the 20 operating lever will both close and open the slide,

Still another object of my invention is to provide means for changing the tonal harmony of an accordion which may be mounted in the interior of the instrument without in any way interfering 25 with its moving parts.

Other objects and advantages of the invention will be apparent during the course of the following description.

In the accompanying drawing, forming a part 30 of this specification and in which like numerals are employed to designate like parts throughout the same,

Figure 1 is a view in plan of a panel which is positioned between the bellows and treble compartment of an accordion, the improved tremulant attachment being applied thereto with portions in section;

Figure 2 is a fragmentary sectional view taken substantially on the line 2—2 of Figure 1.

As disclosed in the accompanying drawing, 40 1 denotes a panel secured within the frame of an accordion and positioned between the bellows 2 and the treble compartment of the accordion. The panel 1 is provided with the longitudinally aligned openings 3 with which are adapted to register the openings 4 provided through the slide 5. This slide 5 is supported in a suitable guideway, generally indicated at 6, for reciprocating movement.

One end portion of this slide 5 is provided with a pin 7 which extends outwardly beyond the panel 1 through a suitably positioned elongated opening 8. This pin 7 provides a means whereby the 45 slide 5 may be moved endwise to bring the open-

ings 4 thereof into or out of register with the openings 3 of the panel 1.

The aligned openings 3 are positioned substantially central between the openings 9 and 10 which provide communication with the tremolo tubes 11 5 and 12 respectively. These tubes 11 and 12 extend inwardly of the bellows 2 and are provided in their sidewalls with the openings 14. The opening 14 of the tube 11 has associated therewith an outwardly opening fluttering valve 15. This valve 10 15 has its inner end suitably secured, as at 16, to the free end portion of the tube 11 while the outer or free end portion of the valve 15 is weighted, as at 16', to assure the desired tonal sound when using the tremolo. The tube 12 has 15 associated with its opening 14 the inwardly opening fluttering valve 17 suitably secured, as at 18, to the outer end portion of the tube 12 with the opposite end portion weighted, as at 19, to also cause the desired tonal sound.

Suitably anchored, as at 20, to the outer face of the panel 1 is a skeleton frame or plate 21. This frame or plate 21 is to one side of the aligned openings 3 and is provided at one end with the guide 22 for the endwise movable master lever 23. 25 This lever 23 is of desired length and has one end portion overlying the frame or plate 21 and said overlying portion is provided with the longitudinally disposed slot 24 through which is directed a headed member 25 carried by the frame or plate 30 21. This headed member 25 coacts with said overlying end portion of the lever 23 to further maintain the same in desired position and said headed member coacts with the opposite end portions of the slot 24 whereby the extent of endwise movement of the lever 23 is limited in either direction.

Pivots connected, as at 26, to the end portion of the frame or plate 21 remote from the guiding means 22 is an end portion of a rock arm 27. The outer end portion of this arm 27 is provided with a longitudinally disposed open slot 28 in which is received a pin 29 eccentrically carried by a wheel 30 suitably mounted, as at 31, upon the panel 1 for turning movement. This wheel 30 45 carries a second eccentrically mounted pin 32, herein disclosed as spaced ninety degrees from the pin 29. This pin 32 is received within the longitudinally directed open slot 33 in one end portion of a lever 34. This lever 34 is pivotally mounted, as at 35, at a desired point intermediate its ends and the opposite end portion of this lever 34 overlies the slot 8 and said second end portion of the lever 34 is provided with a longitudinally disposed open slot 36 which receives the 50 55

outer end portion of the pin 7 hereinbefore referred to.

It is believed to be obvious that upon swinging movement of the arm 27 the lever 34 will be rocked to endwise move the slide 5 in accordance with the extent of rocking movement of the arm 27.

The pivoted end portion of the arm 27, as herein disclosed, is provided with the oppositely disposed and laterally directed fingers 37 to the outer end portions of which are pivotally connected, as at 38, end portions of the elongated and substantially straight pawls 39. These pawls 39 terminate closely adjacent to the guiding means 22 and said end portions are constantly urged one toward the other by a retractile spring 40 secured to and interposed between the inner or pivoted end portions of the pawls 39. As illustrated in Figure 2 of the drawing, this retractile spring 40 serves to maintain the pawls 39 in convergence resulting from the contact of the outer end portion of one of the pawls 39 with the outer or second pawl. The free end portions of the pawls 39 overlie the adjacent portion of the master lever 23 and said outer or free end portions of the pawls 39 are maintained in close contact with said master lever 23 by the guide loop 41 secured to the frame or plate 21 and straddling the adjacent portion of the master lever 23 and the outer or free extremities of the pawls 39.

The outer end portion of the master lever 23 has operatively connected therewith, as at 42, an end portion of a rod 43 which is freely directed through a guide sleeve 44 suitably secured, as at 45, to the panel 1. The outer end portion of this rod 43 is tide or coupled by a bracket plate 46 with the plunger 47 slidably disposed, as at 48, through the bellows frame with the outer end portion of the plunger 47 carrying an operating button 49.

The connection 42 between the rod 43 and the master lever 23 provides a stop with which engages the spring arms 50 suitably anchored, as at 51, to the panel 1 at opposite sides of the lever 23. These spring arms 50 serve to constantly urge the lever 23 together with the rod 43 and the plunger 47 outwardly, the tension of these spring arms 50 being increased when said master lever 23 is forced inwardly as a result of pressure upon the button 49.

The inner end portion of the master lever 23 closely adjacent to the slot 24 thereof is provided with an upstanding lug 52 for ecaction with the inwardly disposed blades 53 carried by the free end portions of the pawls 39.

In Figure 1 of the drawing the parts are shown in their relative positions after the slide 5 has been moved to its open position and with the lug 52 in position to contact with the outer end of the blade 53 of the lower pawl 39 as illustrated in Figure 2, so that upon pressing the button 49

inwardly the lug 52 will contact the outer end of the blade 53 of this lower pawl 39 to swing the rock arm 21 in a direction whereby the slide 5 is moved into closed position to permit the desired tremulant effect to be produced through the tubes 11 and 12. During this movement the pawls 39 are moved in opposite directions whereby the relation of the pawls 39, as illustrated in Figure 1, will be reversed and the lug 52 will be in position for contact with the outer end of the blade 53 of the second pawl 39 when pressure is again imposed upon the button 49 to move the slide 5 back to open position. After this operation the lever 23 will again be moved outwardly so that upon successive inward movement thereof the slide will be caused to be shifted into closed position again. It will, therefore, be readily understood that the tremulant effect may be made effective or discontinued at the will of the player.

It is to be understood that the form of my invention herein shown and described is to be taken as a preferred example of the same and that certain changes in the shape, size and arrangement of the parts may be made without departing from the spirit of my invention or the scope of my claims.

Having thus described my invention, I claim:

1. In an accordion having a panel on the bellows frame at the keyboard side, tremolo tubes carried by the panel, said panel having openings therethrough independent of the tubes, a slide carried by the panel, said slide when in one position closing the openings and when in a second position opening the same, a plunger extending exteriorly of the accordion, and means carried by the panel and coacting with the slide to alternately move the slide into open or closed position upon operation of the plunger.

2. In an accordion having a panel separating the bellows from the keyboard side of the accordion, said panel having a tremolo tube and an opening; a slide movable into open or closed position with respect to the opening, a master lever, means for mounting said lever on the panel for endwise movement, a plunger extending exteriorly of the accordion and operatively connected with the master lever for manually moving said lever in one direction, automatic means for moving the lever in the opposite direction, a rock arm carried by the panel, means carried by the panel coacting with the slide and with the rock arm for moving the slide into open position upon movement of the rock arm in one direction and for moving the slide into closed position upon movement of the rock arm in the opposite direction, and coacting means carried by the master lever and the rock arm for alternately moving the slide into open and closed position upon successive manual operations of the master lever.

MICHELE DE BELLIS.
